US00D957426S

(12) **United States Design Patent** (10) Patent No.: **US D957,426 S**
 Subrahmaniyan et al. (45) Date of Patent: ** Jul. 12, 2022

(54) **DISPLAY SCREEN WITH GRAPHICAL USER INTERFACE**

(71) Applicant: **GE Global Sourcing LLC**, Norwalk, CT (US)

(72) Inventors: **Neeraja Subrahmaniyan**, Niskayuna, NY (US); **James D. Brooks**, Schenectady, NY (US); **Robert Johnston**, Schenectady, NY (US)

(73) Assignee: **Transportation IP Holdings, LLC**, Norwalk, CT (US)

(**) Term: **15 Years**

(21) Appl. No.: **29/704,703**

(22) Filed: **Sep. 6, 2019**

Related U.S. Application Data

(62) Division of application No. 29/597,322, filed on Mar. 16, 2017, now Pat. No. Des. 864,224.
